UNITED STATES PATENT OFFICE.

EDMUND WISEMAN, OF LUTON, ENGLAND.

TENSION MECHANISM OF STRAW-PLAIT-SEWING MACHINES.

1,137,250.

Specification of Letters Patent. Patented Apr. 27, 1915.

Original application filed August 30, 1913, Serial No. 787,511. Divided and this application filed February 3, 1914. Serial No. 816,166.

To all whom it may concern:

Be it known that I, EDMUND WISEMAN, a subject of His Majesty the King of Great Britain, residing at London Road, Luton, in the county of Bedford, England, have invented certain new and useful Improvements in or Relating to the Tension Mechanism of Straw-Plait-Sewing Machines; and I do hereby declare the following to be a full, clear, and exact description of the invention, such as will enable others skilled in the art to which it appertains to make and use the same.

This invention has reference to that class of straw plait sewing machines wherein sewing implements or needles attached to a carrier beneath the work plate, are thrust upward through the work and coöperate with one or more looping devices supported above and movable with the presser foot. Sewing machines of this class are described in my patents, Nos. 228711 and 565585 and also in Johnson's British Patent No. 5926 of 1886.

My invention has particular relation to sewing machines of the class aforesaid provided with intermittent tension mechanism whereby the tension is automatically opened and closed by a tension cam at appropriate periods during each stitch, such for example as is described in my U. S. Patent No. 243023; and relates more especially to those sewing machines which are provided with variable intermittent tension mechanism such for example as is described in Johnson's said British patent, wherein a tension cam is mounted and adjustable laterally on the main shaft and connected with the devices for changing the feed movement, so that by shifting the cam laterally the stitch is altered, one of the operating inclines of said cam extending obliquely around the cam so that lateral movement of the latter will vary the timing of one of the closings of the tension by causing a different portion of this oblique incline to act on the tension lever which operates the tension proper.

The object of my invention is to improve the quality of the work produced and to this end my invention consists in improvements in the said intermittent tension mechanism designed to give a more effective thread control and consisting principally in the provision of a tension cam designed to give a greater number of more appropriately

timed openings and closings of the tension during each stitch than heretofore.

In known intermittent tension mechanism, such for example as is described in my said Patent No. 243023 and also in Johnson's said British patent, the tension cam is furnished with inclines arranged to open and close the tension twice during every stitch for all lengths of stitches; a known modification of cam for variable intermittent tension mechanism adds inclines which give a further rapid opening and closing for the shorter stitches only.

According to my invention, with the object of drawing up all stitches from the longest to the shortest in the most perfect manner possible, I provide the tension cam with inclines so arranged as to give four openings and four closings of the tension at the most appropriate times during every stitch, for stitches of all lengths, and I also, in the case of a cam for variable intermittent tension mechanism, modify the contour of the oblique incline of the cam which closes the tension at variable times, so as to obtain very accurate and effective timings of the closings of the tension for the stitches intermediate of the longest and shortest. My improved tension cam also permits me to advantageously dispense with means such as described in my said Patent No. 243023 and in Johnson's said British patent, for automatically varying the degree of tension exerted on the thread by the act of altering the stitch, and in lieu of automatic means for changing the degree of tension I preferably use hand operated means, such as will be hereinafter described, whereby the degree of tension may be instantly altered and restored again to the exact degree to which it was originally adjusted by the screw tension stud. It is to be understood that my improved tension cam, when adapted for variable intermittent tension, operates or is operated by the feed changing devices in the known manner, my invention being as before explained directed to causing the tension cam to give additional openings and closings of the tension during every stitch and to time said openings and closings more appropriately and accurately.

In the annexed drawings in which similar letters refer to like parts in all the figures:—Figure 1 is a part sectional plan view

showing a sewing machine of the kind described embodying my improvements those parts of the machine not necessary for a clear understanding of the invention being omitted. Fig. 2 is a transverse section through Fig. 1, showing the tension cam and tension proper and the hand operated means for varying the degree of tension. Fig. 3 is an end view of my improved tension cam looking from the right. Fig. 4 is a development of a portion of this cam.

My improvements in the intermittent tension mechanism are shown in the drawings as applied to variable intermittent tension 15 mechanism similar to that described in Johnson's said British Patent No. 5926 of 1886, and to facilitate the identification of the parts shown in my drawings and described in Johnson's said patent I have designated them by reference letters and numerals corresponding with those on the drawings of Johnson's said British patent.

J is my improved tension cam moved laterally on the main shaft D by the lever N', 25 see Figs. 1 and 2, and adapted to shift the position of the variable feed eccentric M to change the length of stitch by means of the lever 107 in the known manner.

88 is the tension lever whose roller is held 30 spring pressed against the cam J, and 809 is a screw carried by lever 88 the end of which screw at the proper times is caused to strike the end of the tension stud 84 and open the tension, also in the known manner.

85 My improved tension cam is designed as before stated to give at the most appropriate times during each stitch, four openings and four closings of the tension, and to this end is constructed with eight inclines, as seen in 40 Figs. 3 and 4. These inclines are designated by the numerals 1 to 8, the odd numbers indicating the inclines which open the tension and the even numbers the inclines for closing it. Inclines 1 to 7 extend parallel with 45 the cam axis, and incline 8, which gives the variable closing of the tension extends obliquely around the cam. The longer stitches are produced when the side marked L (Fig. 4) of the cam is opposite the roller 50 of the tension lever 88, and the shorter stitches are produced when the side marked S is opposite said tension lever roller. The cam makes one complete revolution for every 55 stitch, and has its inclines so spaced and arranged, and is so set upon its shaft, that the timings of the openings and closings of the tension will be substantially as follows:— Incline 1 opens the tension for all lengths of 60 stitch just before the needle eye reaches the top of the needle plate, the tension remaining open long enough to prevent any strain on the thread while the eye of the needle is passing through the work. The roller of the tension lever 88 now arrives at incline 2 65 and the tension closes and remains closed

until the needles approach the top of their stroke, when incline 3 opens the tension which is kept open until the looper and threader have respectively engaged their loops when the roller of tension lever 88 reaches incline 4 after which the tension is closed and remains closed until the looper commences its retreat, this time of closing materially assisting in drawing up the loop. Incline 5 now opens the tension which is held open until the threader begins to back out of its loop, when the tension lever roller reaches incline 6 and the tension closes, remaining closed on the longer stitches until about the time the ascending feed reaches the plate, and remaining closed a little longer on the shorter stitches owing to the stepped contour of incline 7, the object of here keeping the tension closed longer on the shorter stitches being to provide for less free thread passing through the tension when sewing the thinner plaits or braids which are usually sewn with these shorter stitches. Incline 7 now opens the tension and the time it remains open will be governed by movement of the cam laterally on its shaft, which causes the roller of the tension lever to travel across different parts of the closing incline 8 which extends obliquely around the cam. It will be noted 95 that this incline 8 is not continuous, as in the known tension cam, but is stepped about midway of its length, and this special contour assists materially in the drawing up of the stitches intermediate of the shortest and 100 longest. The incline 8 closes the tension for the shortest stitch at about the time the feed commences its advance, and for the longest stitch slightly before the feed has completed its travel. The cycle now recommences.

With tension mechanism arranged and adapted to operate as above described I find as before stated that it is neither necessary nor advisable to employ means for automatically varying the degree of tension by 110 the act of changing the length of stitch, and I provide means for altering the degree of tension by hand and for instantly restoring the original degree of tension determined by the usual screw tension stud.

The tension proper shown in the drawings is similar to that shown in Johnson's said British patent, but in lieu of connecting the pin 228, which extends from the sliding sleeve 81 of the tension through a slot in the sleeve boss, by a link with an arm of the tension cam shifting lever N', I pivot inside the casing of the machine a lever o carrying at its free end an incline o' adapted to bear on the said pin 228 of the sliding sleeve 81, 120 and to the exterior of the casing I pivot the hand lever p. A pin p' extends from the lever o through a slot in the casing and engages in a notch in the lever p, whereby the two levers p and o move together. On mov- 125

ing the hand lever p the incline o' acting on the pin 228 will move the sleeve 81 endwise to compress the tension spring 85 and increase the degree of tension, and on moving back the hand lever to its original position, the slot in the casing constituting a stop to limit its movement, the original degree of tension determined by the screw tension stud 84 will be restored.

10 Although I have described with reference to and shown in my drawings my improved tension cam as arranged for and applied to a well known kind of variable intermittent tension mechanism, it is to be understood 15 that a tension cam arranged to give four openings and four closings of the tension during every stitch, at the times stated, may with advantage be used in a sewing machine of the class described having mechanism 20 which is intermittent without being variable and wherein the tension cam does not move laterally on its shaft when the stitch length is altered. In this case the oblique stepped incline 8 would be dispensed with 25 and an incline parallel with the cam axis substituted therefor, said incline being arranged to close the tension for all lengths of stitches at sometime between the commencement of the feed advance and the completion 30 of its travel, according to the length of stitch being used.

The tension mechanism above described is very advantageously used in conjunction with the controller mechanism locking 35 means described in the specification accompanying my application for U. S. Patent Serial No. 787511, filed August 30, 1913 of which the present application is a division.

What I claim and desire to secure by Letters Patent in the United States is:—

1. A sewing machine, embodying therein thread tensioning mechanism, and controlling means therefor comprising a revolute cam having a series of eight successive peripheral inclines, seven of said inclines extending parallel with the cam axis and one of said inclines extending obliquely around said cam, said inclines being adapted to alternately open and close said tensioning mechanism eight times during each revolution of said cam.

2. A sewing machine, embodying therein thread tensioning mechanism, and control-

ling means therefor comprising a revolute cam having a series of eight successive peripheral inclines, seven of said inclines extending parallel with the cam axis and one of said inclines extending obliquely around said cam and being stepped about midway of its length, said inclines being adapted to alternately open and close said tensioning mechanism eight times during each revolution of said cam.

3. A sewing machine, embodying therein thread tensioning mechanism, controlling means therefor comprising a revolute cam having a series of eight successive peripheral inclines, seven of said inclines extending parallel with the cam axis and one of said inclines extending obliquely around said cam and being stepped about midway of its length, said inclines being adapted to alternately open and close said tensioning mechanism eight times during each revolution of said cam, and means for shifting 75 said cam laterally whereby said last named incline varies the timing of a predetermined closing of said tensioning mechanism.

4. In a straw plait sewing machine, the combination with thread tensioning mechanism, of a revolute tension cam coöperating therewith, and means on the periphery of said cam for opening and closing said tensioning mechanism eight times during each revolution of said cam to produce stitches 85 relatively loose on the short top portion of the stitch and relatively tight on the long under portion of the stitch.

5. In a straw plait sewing machine, the combination with thread tensioning mechanism, of a revolute tension cam coöperating therewith, and a series of successive inclines on the periphery of said cam adapted to open and close said tensioning mechanism eight times during each revolution of 95 said cam to produce stitches relatively loose on the short top portion of the stitch and relatively tight on the long under portion of the stitch.

In testimony whereof I have hereunto set 100 my hand in the presence of two witnesses.

EDMUND WISEMAN.
